BELT BUCKLE

Bernard A. Kohnke, Chicago, Ill.

Application April 20, 1939, Serial No. 268,925

1 Claim. (Cl. 24—191)

This invention relates to an improved type of fastening device for use with substantially open face belt buckles. It has been found that the gripping devices of present buckles in commercial use are not suitable for open face buckles inasmuch as the gripping levers tend to exert too great a force on the cut-out monogram in the face of the buckle and distort same.

An object of the invention is to provide a belt buckle which will securely hold an inserted belt and at the same time position the belt in such a manner that it will not bulge through the open face thereof.

Another object is the provision of a buckle which will permit the use of filigree work due to the absence of the customary exerted pressure set up by an inserted belt.

A further object is the provision of spaced apart gripping fasteners near the peripheral edge of a belt buckle which tend to impress an inserted belt to the frame of the buckle body in such a manner that the belt will not contact the open face of the buckle.

A still further object is the provision of a belt buckle with a minimum of parts which permit ease of operation.

These and other objects and features of the invention will be apparent in the following specification and will be defined in the claim hereto annexed:

In the drawing,

Fig. 1 is a face view of the buckle in association with a belt.

Fig. 2 is an enlarged sectional view taken on line 2—2 of Fig. 1.

Fig. 3 is a vertical cross-sectional view taken on line 3—3 of Fig. 1.

Fig. 4 is a view similar to Fig. 3 illustrating a modification of my invention.

Fig. 5 is a top plan view of the buckle shown in Fig. 4, with parts being broken away and parts being shown in section.

Referring more in detail to the drawing, I may provide a body member comprising a front plate 1, having projecting side flanges 2, which flanges are in turn bent inwardly, as at 3, to form guides for an inserted belt end 4.

As a feature of my invention I may provide a lever 5 which may extend transversely between opposite flanges 2 and may be pivotally attached within and to said flanges by means of pivot pins 6. It will be noted, in referring to Fig. 2, that the lever 5 is pivotally connected at the lower

portion of flanges 2 and is positioned adjacent the peripheral edge of the buckle body.

The lever 5 comprises a plate 7 which is provided with an aperture 8. Disposed at substantially right angles to the plane of the plate 7, adjacent each of the pivot pins 6, are spaced apart lugs or clamping members 9 and 9'. The upper faces of each of the lugs 9 and 9' are serrated, as indicated at 10, whereby the serrated surfaces of said lugs function as supports to grip the belt 4 adjacent its opposite edges and clamp said belt tightly against the buckle body 1. In this manner the threading end of the belt 4 may be detachably secured in the buckle. The opposite end of the belt 4 may be looped through the aperture 8, as indicated at 11, and may be stitched or otherwise fastened.

In view of the fact that the clamping action of the lugs 9 and 9' is confined adjacent the side edges of the belt and no positive clamping action takes place at the longitudinal central portion of the belt, there is no force which would tend to squeeze the central portion of the belt through apertures 12 provided in the face of the buckle body. In this manner the central portion of the belt would tend to belly or sag away from the open face of the buckle, as shown at 13, and would not be associated with the filigree work, cut-out monogram or other insignia on the face of the buckle. It will also be noted that the width of the clamping members 9 and 9' is substantially that of the outer frame portion 14 and that the force of the clamping members is exerted solely against this frame portion, avoiding any strain or stress on the cut out portion defined therein. This absence of strain on the monogram will avoid distortion or severance thereof from the frame body.

As a modification of my invention (Fig. 4 of the drawing), I may provide a positive means of forcing the belt away from the central portion of the buckle face. The buckle may be constructed in the manner above described and may be modified by providing diagonal ridges 15 on the upper face of each of the lugs 9 and 9'. The diagonal ridges 15 may be disposed at an angle to the plane of rotation of the lugs 9 and 9' and may resemble the threads of a worm gear. The pitch of the ridges on each lug may be positively disposed and may function to exert an inward thrust when said lugs are rotated into contact with the face of the belt 4 whereby the central portion of the belt is bent, as indicated at 13. By means of these provisions it will be noted that in addi-

tion to there not being any force tending to squeeze the central portion of the belt through the apertured face of the buckle body, the oppositely pitched ridges 15 provide a positive means whereby the central portion of the belt is forced away from the apertures in the face of the buckle body.

The term "filigree work" as used in the specification and claim is defined as any delicate monogram, insignia or symbol which may be cut out of the face of the buckle or detachably positioned in the frame work thereof.

It will be seen that various modifications in the details of construction may be made without departing from the spirit of my invention and I therefore do not wish to be restricted to the precise details hereinabove set forth except as so limited by the appended claim.

I claim as my invention:

A belt buckle comprising a frame portion, filigree work secured to the inner periphery of said frame, said frame having flange portions extending horizontally thereof and terminating in members forming guideways therewith extending 5 downwardly and inwardly therefrom, a lever member having an opening therein adapted to engage a belt end and being pivotally mounted in and extending between the flange portions, a pair of spaced apart clamping members provided with 10 diagonal ridges on the upper faces thereof formed on said lever adjacent to the inner sides of said flanges and of a width substantially that of the frame portion, the said clamping members being adapted to act essentially against the horizontal 15 portions of said frame adjacent to a vertical portion thereof.

BERNARD A. KOHNKE.
